(57) **CLAIM**

The ornamental design for a motion controller, as shown and described.

DESCRIPTION

FIG. 1 is a perspective view of a motion controller showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a cross-sectional view taken along line 9-9 in FIG. 5;

FIG. 10 is a perspective view of the trigger of the motion controller in FIG. 1 shown in isolation to make clear all aspects of the design; and,

FIG. 11 is another perspective view of the trigger of the motion controller in FIG. 1 shown in isolation to make clear all aspects of the design.

The dashed broken lines illustrate portions of the motion controller and form no part of the claimed design. The dot-dash lines define the bounds of the claimed design and form no part thereof.
